UNITED STATES PATENT OFFICE.

JOSEPH F. JONES, JR., OF BAKERSFIELD, CALIFORNIA.

PUMP.

1,152,734.

Specification of Letters Patent.

Patented Sept. 7, 1915.

Application filed May 14, 1914. Serial No. 838,437.

To all whom it may concern:

Be it known that I, JOSEPH F. JONES, Jr., a citizen of the United States, residing at Bakersfield, in the county of Kern and State 5 of California, have invented new and useful Improvements in Pumps, of which the following is a specification.

This invention relates to a compressed air lift system for pumping water or oil, or 10 water and oil with solids in suspension, from wells, sumps, pits, etc.

It is one of the objects of the present invention to provide a simple, practical air lift pump with a novel form of air lift mechanism by which the air is discharged into the flow pipe at a plurality of points to effectively lift a column of liquid; and also to provide means by which a spiral or rifling motion is imparted to the ascending water 20 and air.

Further objects will hereinafter appear.

The invention consists of the parts and the construction and combination of parts as hereinafter more fully described and 25 claimed, having reference to the accompanying drawings, in which—

Figure 1 is a vertical central section of the well, showing the application of the invention. Fig. 2 is a plan view of the nozzle 30 proper. Fig. 3 is a vertical central section on the line $x-x$, Fig. 2. Fig. 4 is an end view of the nozzle.

Referring to the drawings, A indicates the casing of a well and 2 the surface frame 35 from which the flow or discharge pipe 3 is hung. Extending down through the flow pipe to within a short distance of the lower end of same is an air pipe 4, and secured on the end of said pipe is a discharge nozzle 40 casing 5. The upper end of the flow pipe is provided with a T-fitting, as at 6, through one side of which the water is permitted to discharge, and the upper end of said fitting is provided with a plug 7 in which the air 45 pipe is secured.

The air discharge nozzle proper, which is more clearly shown in Figs. 2, 3 and 4, includes an inverted T-shaped casing 5 to which the lower end of the air pipe is connected, as at 8. Positioned on opposite sides of the air pipe 4, and eccentric to pipe 3, are nozzles 9 and 10 connected with an interior air passage 11 in casing 5 and communicating with a suitable source of air 55 supply under pressure through the pipe 4. The discharge opening 12 in each nozzle is

preferably tapered to give the discharging air a greater velocity. If desired, the nozzles 9—10 may be given an opposite tilt to throw their axes out of parallelism with the axis 60 of the flow pipe in order to impart a uniform swirling or spiral motion to the column of liquid moved by the device.

In operation, the pressure in the air pipe must be greater than the hydrostatic pressure of the water at the bottom of the pipe and in quantities sufficient to make the ascending column of air and water in the flow pipe lighter in its total height than the weight of an equal column of solid water 70 of the depth of the well from the surface of the water to the bottom of the pipe. The air discharging through the angularly positioned eccentric nozzles imparts a spiral motion to the water and also causes the air to 75 become evenly distributed, thereby helping or increasing the lifting efficiency within the flow pipe. The velocity created by the tapered openings in the nozzles is also taken advantage of in this instance as it gives an 80 impact to the water which further aids the lifting efficiency. The spiral motion imparted by the discharging air from the angularly positioned nozzles is of great advantage where more or less solid material, such as 85 sand and gravel, is liable to enter the flow pipe, as the spiral motion of the water keeps the solid particles in constant agitation and motion which permits it to be discharged with the ascending or outflowing column of 90 water.

An air lift designed as here shown is simple in construction and may be easily applied to any standard form of well, as it is only necessary to provide a surface frame 95 by which the flow and air pipes may be suspended.

A suitable form of valve 14 may be provided for the purpose of controlling the volume of air admitted to the well and a 100 valve 15 may be provided on the outlet pipe for the purpose of closing same when it is desired to blow back or clear the lower end or intake of the flow pipe from obstructing materials.

The materials and finish of the several parts of the pump are such as the experience and judgment of the manufacturer may dictate. Various changes in form, proportions and minor details of construction may 110 be resorted to within the scope of the appended claim and I do not wish to limit my

self to the specific design and construction here shown.

Having thus described my invention, what I claim and desire to secure by Letters Patent is—

In a compressed air lift pump, the combination with an outer circular flow pipe, of an air pipe concentrically positioned therein and extending to a point adjacent 10 the lower end thereof to provide an annular space between said flow pipe and said air pipe, a T-shaped casing secured on the lower end of said air pipe and having its opposite ends closed, a discharge nozzle projecting at 15 substantially right angles from said casing on diametrically opposite sides of said air

pipe substantially midway of said annular space, said nozzle being inclined to the vertical and discharging upwardly to produce a spiral motion around said air pipe, the 20 construction and arrangement of parts being such that air bubbles move inwardly toward the air pipe and decrease the friction between the surface thereof and the body of ascending water.

25

In testimony whereof I have hereunto set my hand in the presence of two subscribing witnesses.

JOSEPH F. JONES, JR.
